BRASSIERE

Alfred Egon Maas, New York, N.Y., assignor to Maidenform, Inc., New York, N.Y., a corporation of New York

Filed Aug. 28, 1964, Ser. No. 31,491

Term of patent 14 years

(Cl. D20—4)

The figure is a perspective view of a brassiere showing my new design, the portion of the back not shown is conventional and unornamented.

I claim:

The ornamental design for a brassiere, as shown and described.
